CLAIM

The ornamental design for a container recess, as shown and described.

DESCRIPTION

FIG. 1 is a right upper perspective view of a container recess illustrating our new design;

FIG. 2 is a front view thereof;

FIG. 3 is a right side view thereof, the left side and right side views being identical; and,

FIG. 4 is a top view thereof.

All dashed lines are for environmental purposes only and form no part of the claimed design.
